Thomas Wall

UNITED STATES PATENT OFFICE.

THOMAS WALL, OF JONES STATION, OHIO.

BEDSTEAD.

Specification of Letters Patent No. 28,621, dated June 5, 1860.

To all whom it may concern:

Be it known that I, THOS. WALL, of Jones Station, in the county of Butler and State of Ohio, have invented a new and useful Improvement in Bedsteads; and I do hereby declare that the following is a full and complete description of the same, reference being had to the accompanying drawings and letters of reference marked thereon, making 10 a part of this specification.

Figure 1 is a perspective view of a complete bedstead in the construction of which my improvements are employed. Fig. 2 is a vertical section through the center of one 15 of the posts and of the ratchet, pawl and a portion of one of the side rails. Figs. 3 and 4 are end views of parts to be described.

My invention relates to the manner of connecting the side rails of a bedstead to the 20 corner posts thereof and retaining them in place, also to an improved device for tightening the bed cord when the same is applied to the bedstead in the manner herein described.

A B C D are the four corner posts of a 25 bedstead of the ordinary general construction.

E F are the side rails which are round and have tenons formed upon their ends which enter appropriate mortises in the corner 30 posts. The tenons and mortises by which the ends of F are united to the corner posts are square, and the rail F is thus prevented from turning around in the mortises by the strain of the bed cord upon the pins placed 35 upon the periphery of the rail as will be explained. The rail E has round tenons and the mortises or holes in the posts which they enter are also round. The ends of the side rails E and F each pass through flanged 40 sockets d, d, e, f. The apertures through these sockets are of the size and shape of the tenons respectively, the ends of the rails projecting through far enough to form the tenons which have been mentioned, and the 45 unflanged end of the sockets affording the shoulders which bear against the surface of the posts around the mortises or holes into which the tenons penetrate. A pin (g) secures the sockets to their places on the rails. 50 G G are end rails which are framed into the corner posts either by a mortise and tenon or by a right and left screw or any other familiar and approved mode.

(k k k) are clasps or hooks fastened to 55 posts B C D and hooking or clasping the flanges of the sockets d, d, f, respectively

serve to retain the side rails in union with the corner posts, and in connection with the hook latch h preserving the bedstead frame firm and secure. The periphery of the 60 flange to socket (e) is notched or serrated to constitute it a ratchet wheel, to the under or lower side of which the hook latch (h) is adapted. This latch is constructed with a U shaped part, an arm of which passes back 65 upon two opposite sides of the square part of post A at a point in a horizontal line with the lower or under edge of the flange or ratchet e, and a pin (i) passes through the post from side to side and through the ends 70 of these arms forming a center or pivot upon which the latch moves. The latch proper extends from the transverse part of the U shaped part which has been described and having a sectional form adapted to the 75 teeth of the ratchet (e) as shown in Fig. 3, it enters the notches or spaces between the teeth appropriately, and prevents the same from rotating in an adverse direction when the rail to which the ratchet is secured is 80 acted upon by the cords as will be explained.

j is a spring fastened by one end to the post A and its other end applied to the ratchet latch h as shown, causing it to remain in contact with the ratchet and enter 85 the notches or recesses appropriately as the side rail and ratchet are rotated. This latch has a hook or clasp which takes hold upon the outer surface of the ratchet and retains the part including the tenon of the 90 side rail to which it is secured in its place in union with the corner post.

The side rails E and F are each furnished with a series of bed pins (a) projecting from the periphery of each to receive the 95 bed cord b. The end rails G also have each a central bed pin (c). The bed cord b being secured by one end to a pin in one of the side rails nearest to one of the corner posts, is extended across the bed frame 100 passing, the first time across, around the central pin c in one of the end rails G and thence around a pin in the side rail opposite to the one from whence it first started and thence back and around the next pin to 105 the one from whence it began, and thence back to a next pin upon the opposite side and so on back and forth around each pin upon the opposite sides, in their regular order until all the pins are encompassed by 110 the cord, the cord passing the last time across around the central pin in the end rail G op-

posite to and corresponding with the pin in the end rail around which the cord was passed the first time it was carried across as explained. The last end of the cord is 5 then properly secured.

The frame now being together properly, and the bed cord having been applied as described it is prepared to be tightened so as to be rendered sufficiently firm to maintain 10 the weight of a bed or mattress and an occupant without swagging or becoming unduly depressed in the center. The side rail E or the windlass as it may be called, is furnished with a stout pin (l) placed near 15 the center from the two ends. A suitable lever of wood or iron is taken and one end placed under the rail or windlass E at (l). A loop is then formed by passing a rope from the pin (l) over the top of the rail E 20 and around the lever or bar and thence back to (l) where it is properly secured at the other end, thus forming a loop. An outward or downward pressure now exerted upon the outer end of the lever will exert 25 a powerful strain to cause the top of E to rotate outwardly. In doing so it exerts a heavy strain upon all parts of the bed cord, as is manifest, rendering it as tight as may be desired. In the rotation of the side rail 30 E the ratchet (e) is carried around and the latch (h) entering new notches or recesses as they are presented by the revolving of the rail and ratchet, retains the same securely at the point of tension to which they 35 are carried.

Whenever by continued use for a considerable time the bed cord becomes slack,

it is readily restored to a desired tension by the lever and loop employed as explained. The pin (l) may be movable in the hole 40 in E so as to be taken out in case it should, in the revolution of E, present itself upwardly and be found to interfere with the bed when placed upon the bedstead.

An end view of the square tenon of F 45 and of the flanged socket which pertains to it is seen in Fig. 4.

My improvements secure a means of constructing a bedstead which may be easily taken down or put up by one man without 50 tools. The bed cord can also be tightened readily and with ease requiring only the pressure of one person upon the end of a lever to render the rope sufficiently tight for all purposes. The cord (b) passing around 55 the pins (c) in the rails G serves in connection with the hooks or clasps which have been described to retain the frame of the bedstead firmly together.

Having fully described my invention I do 60 not claim any of the parts thereof separately, nor in combination, except as specifically expressed.

What I claim as new and desire to secure by Letters Patent is—

The flanged sockets and hooked fasteners or clasps as described when used in combination with the windlass rail E with its pin l ratchet e and latch h all arranged 65 to operate as and for the purposes set forth. 70

THOMAS WALL.
